ARTICLE RETAINING CLIP

William E. Olson, 429 W. Wells St.,
San Gabriel, Calif.

Filed Apr. 5, 1965, Ser. No. 84,596

Term of patent 14 years

(Cl. D34—5)

The broken line showing of a tee in FIG. 1 is for illustrative purposes only.

I claim:

The ornamental design for an article retaining clip, as shown and described.
